DISPLAY DEVICE

Emil N. Farkas, Chicago, Ill.

Application November 23, 1944, Serial No. 564,878

4 Claims. (Cl. 283—63)

1

This invention relates to new and useful improvements in display devices and more particularly to devices useful as educational or sales aids by portraying objects or functions.

One object of the invention is the provision of a sturdy and relatively inexpensive display device of the type in which transparent sheets bearing indicia are arranged in cooperative relationship with one another.

In display devices of the above-mentioned type the indicia are printed or otherwise applied to sheets of acetate which, on account of their costliness, are usually made extremely thin. These thin sheets, whether used singly or folded in two and bearing indicia visible from both sides, are difficult to handle during manufacture and when the device is in use.

In order to guard against warping, curling or tearing of the thin sheets of acetate, in my joint patent with Frank F. Farkas, No. 2,091,260, dated August 31, 1937, sheets of acetate are cemented to frames of relatively sturdy paper, and in which one or more sheets of acetate bear indicia cooperating with those appearing on the others when the sheets are superimposed and viewed together. While this constituted an important advance in the art, the method and means disclosed therein were expensive because highly specialized machinery and costly adhesives were required.

According to the present invention, an inexpensive and sturdy device is produced by applying the indicia to a sheet of thin transparent flexible material which is formed into two or more folds, and placing between the two layers of each fold a sheet of relatively rigid, inexpensive material, such as paper, provided with a window through which said indicia are visible. Each leaf will thus consist of a triple layer; two relatively flimsy transparent surfaces on the outside and a sturdy paper frame between them. Such leaf can be readily handled without danger of damaging it and will lie flat when not in use.

One of the advantages of my invention is that the triple-layer leaves are sturdy enough to permit their marginal perforation and the use of mechanical binders, such as rings, to hold them together. Without the paper stiffener, thin acetate sheets even when folded in two would fray or tear at perforations and must, therefore, be held together by other means than the convenient mechanical or loose-leaf type of binders.

A further advantage resulting from my invention is that efficient web method of printing can be used to apply the indicia to the thin sheet of

2

acetate which can then be formed into folds to receive the stiffeners.

These and other objects and advantages of the invention will more clearly appear from the claims and the following detailed description of certain preferred embodiments thereof as applied to the drawings in which:

Fig. 1 is a front view of a book with parts broken away, made up in accordance with my present invention; and

Figs. 2, 3 and 4 are transverse cross-sections of books made up in accordance with three different embodiments of my invention.

Referring now to Figs. 1 and 2 of the drawings, 1 is a sheet of acetate folded back upon itself at 2. In the fold is placed a stiffener consisting of a sheet of paper 3 having a window 4 cut therein and through which indicia such as 5, 5' and 5'' which appear on the inside or outside surfaces of the two folds of the acetate 1 may be viewed. The element 5 may appear, for instance, on one inside surface of the topmost acetate fold, the element 5' on one of the inside surfaces of the middle acetate fold, and the element 5'' on the lowermost acetate fold. When the three leaves are superimposed the appearance of the indicia will be as it appears in Fig. 1. When the topmost leaf is turned so that only the middle and the lowermost leaves remain in place, then one will see only the elements 5' and 5'', and when the second leaf is also turned away then one will see on the bottom leaf solely the element 5'.

The triple layer consisting of the folded sheet 35 of acetate 1 and the paper frame 3 is provided with one or more marginal perforations 6 at the edge opposite the folded edge 2 so as to permit the use of mechanical binders, such as rings 7 by means of which two or more triple-layer 40 leaves assembled as above explained can be held together in the form of a book.

The structure thus assembled can be readily handled without danger of damaging the sheets. The sheets will lie flat when the book is opened and the registry between the indicia on the sheets 45 of acetate and the paper frame will be insured.

Fig. 2 illustrates a pamphlet having three triple-layer leaves which are separate from one another and which, as shown in Fig. 1, may be placed 50 between outside covers 8.

In the embodiment shown in Fig. 3, the three leaves of a book are formed from a single sheet of acetate 1a folded into three pockets holding frames 3. The open ends of the folds through 55 which the frames 3 are inserted are perforated as

indicated at 6a and held together by means such as rings 7.

In the structure shown in Fig. 4, the continuous web 1a of Fig. 3 is retained. However, instead of providing a separate frame for each leaf, a sheet of paper 3a provided with two windows 4a, 4b is interleaved with two adjacent folds.

In all these structures, and particularly in Figs. 3 and 4, the acetate is so formed as to permit the use of web printing.

Other modifications will readily suggest themselves to those skilled in the art.

What I claim is:

1. In a device of the character described, a sheet of transparent relatively flexible material folded upon itself and bearing cooperating indicia visible through the folds, and a sheet of relatively stiff material between the folds of the transparent sheet and having a window in alignment with said indicia, the flexible and stiff sheets having aligned perforations along one edge arranged to receive mechanical binding means.

2. The device according to claim 1, and in which the sheet of relatively stiff material substantially fills the space between the folds of the transparent sheet and forming therewith a leaf sufficiently sturdy for handling.

3. In a device of the character described, a plurality of marginally perforated leaves, each comprising a sheet of transparent relatively flexible material folded upon itself and constituting the front and back surfaces of a leaf bearing cooperating indicia, and a sheet of relatively stiff material between the folds of the transparent sheet and having a window in alignment with

said indicia, and marginal perforations aligned with the perforations in the folded leaves.

4. A display book comprising a sheet of transparent and relatively flexible material, a sheet of relatively rigid material contacting on both of its surfaces with the first sheet, the two sheets being formed into triple-layer folds forming the leaves of the book, the outside ones of the triple-layer folds being the transparent layers of each leaf, said outside layers bearing cooperating indicia and the intervening rigid layer having a window in alignment with the indicia, the triple-layer folds forming each leaf being perforated along one edge to accommodate mechanical binding means.

EMIL N. FARKAS.
